UNITED STATES PATENT OFFICE.

JAMES E. SEELEY, OF LOS ANGELES, CALIFORNIA, ASSIGNOR TO
SYCHRONOUS STATIC CO., OF LOS ANGELES, CALIFORNIA, A
CORPORATION OF CALIFORNIA.

OSCILLATING-CURRENT LAMP.

No. 834,496.

Specification of Letters Patent.

Patented Oct. 30, 1906.

Application filed July 12, 1905. Serial No. 239,320.

To all whom it may concern:

Be it known that I, JAMES E. SEELEY, a citizen of the United States, residing at Los Angeles, in the county of Los Angeles and State of California, have invented a new and useful Oscillating-Current Lamp, of which the following is a specification.

The main object of this invention is to provide means for producing rays of definite character—for example, violet rays.

A further object is to provide means for this purpose which will be simple and cheap in construction and safe in operation.

The accompanying drawings illustrate the invention.

Figure 1 is a vertical longitudinal section of the lamp. Fig. 2 is a transverse section on line $x^2 x^2$ in Fig. 1. Fig. 3 is a transverse section on line $x^3 x^3$, Fig. 1. Fig. 4 is a diagram of the circuit connections.

The lamp comprises a primary or exciting coil 1, a secondary coil 2, and electrodes 3, connected to said coils. The coils are arranged in concentric relation, the primary coil being preferably on the outside and forming the side wall or peripheral casing of the lamp.

4 designates a back member or disk, and 5 a front member or disk, said disks being arranged, respectively, at back and front of the lamp and engaging the primary coil, which is held in engagement therewith by any suitable means, such as tie-bolts 6. The back member 4 may be provided with any suitable supporting means, here indicated as a rod 7, and the front member 5 may have a central opening 8 for insertion or attachment of any suitable applicator used in surgical operations or generally for the passage of the rays from the electrodes. Said electrodes may be removably supported in their supporting-standards 9 10, as by means of screws 3', said standards extending inwardly from the peripheral wall of the lamp—that is to say, from the primary coil, the upper standard 10 being insulated from said wall by an insulating-block 11 and the lower standard 9 being connected to the outer end or portion of the primary coil, being provided, for example, with a screw-threaded portion 9', working in a metal nut or head 12, secured to the outer turn of the primary coil. The standard 8 has an insulating knob or

handle 13 on its outer end for manipulation thereof. 14 designates a fastening-nut. 55

The primary coil consists of a few turns of comparatively heavy ribbon or strip metal wound in spiral form and engaging in grooves 15 in the front and back plates 5 4.

Secondary coil 2 consists of a much larger 60 number of turns of smaller ribbon, also wound in spiral form to form a flat or disk coil, which fits within the coil 1 and rests against or close to the back member 4, this ribbon being narrower than that of the primary coil, so as to leave a space or chamber 16 within the primary coil and in front of the secondary coil. Said secondary winding 2 is insulated between the turns on both front and back faces by suitable insulation 24, 70 such as built-up mica. The electrodes 3 are located adjacent to one another directly in the rear of the opening 8 of the front plate of the lamp, so that the rays issuing from the discharge between said electrodes will pass 75 directly through said opening. 22 23 designate binding-posts connected to the primary coil. The lower electrode 3 is connected directly to outer end of coil 1, said coil having a perforation 1' through its windings to permit of passage of standard 10 for said electrodes. The upper electrode 3 is connected by wire 25 to the inner end of coil 2.

The lamp is particularly intended for use with circuits giving a condenser-discharge—85 that is to say, a discharge of moderately high potential and extremely high frequency. Such a circuit is shown in Fig. 4, where 17 indicates an alternating-current-supply circuit, including the primary of step-up transformer 11, whose secondary is connected by circuit-wires 18 18' to a condenser 19, to which is also connected a discharge-circuit 20, including a spark-gap means 21 and the primary coil 1 of the lamp. The alternations in the supply-circuit operate through the transformer to periodically charge the condenser, which discharges through the circuit including the spark-gap and primary coil 1, said circuit being of low impedance, 90 so that the oscillations developed therein will be of high frequency and of large quantity.

I have found that with such high-frequency oscillations the violet rays are developed in large amount without the use of

extremely high potential of oscillating current, and the lamp is thereby rendered comparatively economical and safe in operation. The location of the primary coil on the outside and the connection of the outer end of the secondary to the inner end of the primary also conduce to the safety of the lamp, the exposed parts not presenting potentials that would be dangerous to the operator.

10. Electrodes 3 are of iron in case violet rays are to be produced; but the material of the electrodes may be varied according to the character of the discharge or light desired.

What I claim is—

15. 1. A lamp comprising a primary coil and a secondary coil within the primary coil, a discharge-circuit connected to include the primary and secondary coils in series, and electrodes connected in the discharge-circuit and located in the space within the primary coil, the said primary coil forming a peripheral casing for the lamp, and front and back plate members secured to the primary coil to complete the casing for the lamp, said

front plate having an opening for passage of 25 light.

2. A lamp comprising back and front plate members, the front plate member having an opening, a primary coil located and supported between said members to form a 30 peripheral wall of the lamp, a secondary coil within the primary coil, said secondary coil being of smaller longitudinal dimensions than the primary coil so as to leave a space within the primary coil and in front of the 35 secondary coil, and electrodes arranged within said space in the rear of the aforesaid opening in the front plate member, said electrodes being connected to be energized by said coils.

In testimony whereof I have hereunto set my hand, at Los Angeles, California, this 3d day of July, 1905.

JAMES E. SEELEY.

In presence of—

ARTHUR P. KNIGHT,
FRANK L. A. GRAHAM.
